[57] CLAIM

The ornamental design for an extension attachment for
a telephone earpiece, as shown and described.

DESCRIPTION

FIG. 1 is a front, top and right side perspective view of
an extension attachment for a telephone earpiece showing
our new design;

FIGS. 2 and 3 are respectively front and rear eleva-
tional views thereof;

FIG. 4 is a right side elevational view thereof, the side
opposite being a mirror image thereof; and

FIGS. 5 and 6 are respectively top and bottom plan
views thereof.

FIG. 7 is a top perspective view of a second embodi-
ment thereof;

FIG. 8 is a front elevational view of the second embodi-
ment thereof;

FIG 9 is a rear elevation view of the second embodi-
ment thereof;

FIG. 10 is a side elevation view of the second embodi-
ment thereof taken from the left of FIG. 9;

FIG. 11 is a top plan view of the second embodiment
thereof; and

FIG. 12 is a bottom plan view of the second embodi-
ment thereof.

Fig. 1.

Fig. 2.

Fig. 4.

Fig. 3.

Fig. 5.
